UNITED STATES PATENT OFFICE.

ROBERT W. SCOTT, OF LEEDS POINT, NEW JERSEY, ASSIGNOR TO SCOTT & WILLIAMS, INCORPORATED, OF CAMDEN, NEW JERSEY, A CORPORATION OF NEW JERSEY.

SHAPED KNITTED WEB.

1,179,045.

Specification of Letters Patent. Patented Apr. 11, 1916.

Application filed June 17, 1910. Serial No. 567,507.

To all whom it may concern:

Be it known that I, ROBERT W. SCOTT, a citizen of the United States, residing in Leeds Point, Atlantic county, New Jersey, 5 have invented certain Improvements in Shaped Knitted Webs, of which the following is a specification.

The object of my invention is to provide a simple and efficient means of shaping a 10 knitted web and particularly a seamless tubular web, an object which I attain in the manner hereinafter set forth, reference being had to the accompanying drawings, in which—

15 Figure 1 is a view of a piece of seamless tubular ribbed knitted web intended for the body portion of an undershirt or union suit, said web being knitted in accordance with my invention; Fig. 2 is an enlarged trans- 20 verse section of part of the web taken on either of the lines *a—a*, Fig. 1; Fig. 3 is a similar section taken on the line *b—b*, Fig. 1; Fig. 4 is a view similar to Fig. 3, but illustrating another form of the narrowed 25 portion of the web; Fig. 5 is a diagrammatic illustration of the knitting instrumentalities of a machine arranged for producing the wider portion of the fabric, as shown in Fig. 2; Fig. 6 is a similar view of said knitting 30 instrumentalities as related to each other for the production of the narrow portion of the web, shown in Fig. 3; Fig. 7 is a similar view of said knitting instrumentalities as modified in their relation to each other for 35 the production of the web shown in Fig. 4; Figs. 8, 9 and 10 are views, similar, respectively, to Figs. 5, 6 and 7 but illustrating a modification of my invention.

The object of my invention is to effect 40 change in the diameter of the tubular web so as to contract said web, as, for instance, in the waist portion of a shirt or the ankle or garter portion of a stocking, or to increase the diameter of the web as for instance in 45 the bust or skirt portions of a shirt or the calf portion of a stocking.

My invention consists mainly in employing, usually in the wider portion of the garment, a composite web and in an adjoining 50 portion of the garment, usually the narrower portion, a web of different character, usually a single web having fewer wales than the composite web but knitted continuously with the standing wales of said composite 55 web, a special adaptation of my invention

being that in which the web both in the composite and single portions is ribbed.

As shown in Figs. 1, 2, 3 and 4, I have employed, in the wider portion of the garment, ribbed knitted web of the character set 60 forth in my Letters Patent No. 899,439, dated September 22, 1908, to which I have given the name "interlock rib," the character of the web being changed to ordinary rib in the narrowed portion of the garment. 65

As shown in Fig. 2, the portion A of the web is composed of two ribbed webs with crossed sinker wales, one of these webs presenting alternately produced face wales 1 and back wales 2, and the other presenting 70 alternately produced face wales 3, and back wales 4, the sinker wales of one web crossing those of the other web. In the contracted portion B of the garment, however, ordinary ribbed web is produced, this web, in the fabric shown in Fig. 3, consisting of an ordinary one-and-one rib presenting alternately produced face wales 1 and back wales 2, while in the fabric shown in Fig. 4, the contracted portion of the web presents a 75 two-and-one rib, adjoining face wales 1 and 3 alternating with single back wales 2. 80

The composite ribbed web shown in Fig. 2 is produced in the same manner as described in my former patent, the machine having two sets of needles 1^a and 2^a or 3^a and 4^a (Fig. 5) the needles of each set being 85 so disposed as to produce an ordinary ribbed fabric, the needles 1^a and 3^a being hereafter, for convenience referred to as "cylinder" 90 needles and the needles 2^a and 4^a being referred to as "dial" needles, as they will usually be disposed respectively in a cylinder and dial in a circular knitting machine, although my invention in its broader embodiment is not limited to seamless tubular webs or to the use of a circular machine. 95

The two webs are independently knitted, the yarn being fed to the needles 1^a and 2^a in order to produce one web and to the needles 3^a and 4^a in order to produce the other web, and to cross its sinker wales with that of the first web, as indicated by the plain and dotted lines in Fig. 5. 100

In order to change from the production 105 of this interlock ribbed web to an ordinary one-and-one ribbed web for the contracted portion of the garment stitches, are transferred from the dial needles of one set to the cylinder needles of the other set, and 110

from the cylinder needles of one set to the dial needles of the other set, for instance, the stitches may be transferred from the dial needles 4^a to the cylinder needles 1^a and from the cylinder needles 3^a to the dial needles 2^a, the needles from which the stitches have been transferred being then put out of action and one-and-one ribbed web being knitted upon the remaining cylinder needles 1^a and dial needles 2^a, as indicated in Fig. 6, thus producing a one-and-one ribbed web having one-half the number of wales of the interlock ribbed web.

If a greater number of wales in the contracted portion of the garment is desired, the change may be from the composite ribbed web to an ordinary two-and-one ribbed web having three-fourths as many wales as there are in the composite ribbed web, this change being effected by transferring stitches from every other dial or cylinder needle to the corresponding cylinder or dial needle and then shogging one needle carrier in respect to the other, so that the remaining active needles of one carrier will alternate with active pairs of needles of the other carrier, for instance, the stitches may be transferred from the dial needles 4^a to the cylinder needles 1^a and the dial then shogged so as to cause the needles 2^a to alternate with the pairs of needles 1^a and 3^a, as shown in Fig. 7, the knitting yarn following the course shown in said figure.

It is not necessary that the composite ribbed web shall be one-and-one rib as some or all of the ribs of each member of said web may be composed of a plurality of wales, thus in Fig. 8 I have illustrated an arrangement of knitting instrumentalities for the production of a composite ribbed web, each member of which is composed of two-and-two rib. In order to change this web into a web having one-half the number of wales, two out of three of the needles of one needle carrier may transfer their stitches to the corresponding needles of the other needle carrier, the third needle in the latter carrier transferring its stitch to the corresponding needle of the other needle carrier, thus in Fig. 9 stitches have been transferred from every third cylinder needle 5 to every third dial needle 7^a, from every third cylinder needle 6 to every third dial needle 8^a, from every third cylinder needle 7 to every third dial needle 5^a and from every third cylinder needle 3 to every third dial needle 6^a, the dial needles which thus receive the stitches being the only ones to remain in action, the stitches being transferred from the other dial needles to the corresponding cylinder needles and said dial needles being put out of action, the knitting yarn being then laid upon the needles in the manner indicated in Fig. 9.

When it is desired to produce a two-and-

one web having three-fourths of the number of wales of the composite ribbed web produced as shown in Fig. 8, the stitches are transferred from every other needle of one needle carrier to the corresponding needle of the other needle carrier, and the needle carriers are then shogged so as to bring the remaining needles of one needle carrier between successive pairs of needles of the other needle carrier, thus, as shown in Fig. 10, the stitches have been transferred from every other needle 5^a and 7^a of the dial to the corresponding cylinder needles 5 and 7, and the dial has then been shogged so as to bring the needles 8 between the needles 6 and 7 of the cylinder and the needles 6 between the needles 5 and 8 of the cylinder, the yarn being applied to the needles in the manner indicated in Fig. 10.

When the dial needles are normally in line with the cylinder needles transfer of stitches from the needles of one carrier to those of the other can be effected by what I term "straight transfer" and in making such transfer it is preferable to so manipulate each transferring needle as to transfer the stitch of a course preceding that carried by the needle, or when this is not done, the stitch which is transferred, is, by preference, that of a course underlying the course upon the needles which receive the transferred stitches.

In changing from the narrower to the wider portion of the web the needles which transferred their stitches in effecting the narrowing are reintroduced and resume the formation of stitches for the further production of composite ribbed web, no eyelet holes being produced for the reason that the open loops in the initial course formed on the reintroduced needles are covered by wales of the other face of the web.

Instead of transferring the stitches from one needle to another in discontinuing wales of the composite ribbed web, said stitches may, if desired, be cast from the needles, the standing wales of the web preventing the straining of the wales from which the stitches were dropped to such an extent as to cause said stitches to run back.

I claim:

1. A knitted web ribbed throughout and having contiguous portions, one composed of separate webs interknitted with one another and the other composed of a single ribbed web, wales of the composite web being discontinued at the point of change.

2. A knitted web ribbed throughout and having contiguous portions, one composed of separate ribbed webs interknitted with one another and the other composed of a single ribbed web having its wales started by merging wales of one member of the composite ribbed web into corresponding wales of the other member of the same.

3. The mode herein described of producing a knitted fabric, said mode consisting in first knitting a composite web upon a plurality of sets of needles by first drawing 5 stitches with one yarn upon one set of needles, then drawing stitches with another yarn upon another set of needles and interlocking these stitches with those first produced, then discontinuing the formation of 10 stitches upon certain of the needles and transferring the stitches upon the latter to needles which still remain in action, and then continuing the knitting upon the remaining active needles.

15 4. The mode herein described of producing a knitted fabric, said mode consisting in first knitting a composite ribbed web upon a plurality of sets of needles by drawing

stitches first upon one set of needles with one yarn and then upon the other set of needles 20 with another yarn so as to interlock the two ribbed webs one with the other, then discontinuing the formation of stitches upon the needles of one set and transferring the last formed stitches upon said first set to 25 corresponding needles of the other set, and then producing stitches upon the latter set of needles only.

In testimony whereof, I have signed my name to this specification, in the presence of 30 two subscribing witnesses.

ROBERT W. SCOTT.
